BEVERAGE COOLING AND DISPENSING APPARATUS

Martin Senese, Detroit, Mich.

Application February 26, 1934, Serial No. 712,945

4 Claims. (Cl. 62—141)

The invention relates generally to beverage cooling and dispensing apparatus.

In the usual apparatus where a large quantity of beverage is drawn off in a short period of time, the cooling effect of the brine solution or other cooling medium, when the temperature is high, is inadequate to properly cool the beverage.

The principles of design and construction involved in the present invention overcomes the above disadvantage, and includes the provision of means whereby the temperature of the beverage may be lowered considerably immediately preceding its discharge from the apparatus. This is accomplished preferably by arranging a coil, adapted to contain a portion of the beverage, in operative relation to a body of exceptionally cold cooling medium, preferably below zero, in such a manner that the coil may be lowered and immersed in the cooling medium during the time that the beverage is being withdrawn from a dispensing valve or tap which is arranged adjacent one end of the coil. Means operable by a foot treadle are also provided whereby the dispensing valve may be opened at the same time that the coil is lowered into the cooling medium. Thus the operator is in a position to use his hands to better advantage in serving the beverage.

Another object of the invention is to provide a novel valve operating mechanism with means controlled by the hand arranged in combination therewith for rendering the mechanism inoperative in a manner whereby the valve may be manually operated as desired regardless of whether the coil is lowered or not.

A further object is to provide a device controlled by the foot whereby the means for lowering the coil may be rendered inoperative so that the dispensing valve may be opened and closed as desired.

Another object of the invention is the provision of a novel device by which the foam from the beverage may be wiped and removed from the containers as they are filled. This device is preferably attached to the valve or nearby, so that as each container is filled it may be lifted up and swung in a horizontal position in order that the wiper blade of the device will engage the top of the container.

Other objects and advantages of the invention will appear after considering the description hereinafter set forth in connection with the drawings hereto annexed wherein the various details of the structure are clearly shown.

With reference to the drawings:

Figure I is a front view in elevation of the beverage cooling and dispensing apparatus;

Figure II is a sectional view taken substantially on line 2—2 of Fig. I, and clearly sets forth the manner in which the majority of the working parts are operatively related to each other;

Figure III is a section taken on line 3—3 of Fig. II, and shows the valve operating mechanism, and a part of the means for rendering the valve inoperative;

Figure IV is a section taken on line 4—4 of Fig. II, and shows in detail how the dispensing valve may be operated without lowering the coil which is adapted to be immersed in the cooling medium;

Figure V is a sectional view taken on line 5—5 of Fig. III, and shows more in detail the means for rendering the valve operating mechanism inoperative;

Figure VI is a section taken on line 6—6 of Fig. II, and shows on a larger scale the construction of the device which is used for wiping the foam from the beverage containers as they are filled; and

Figure VII is a section taken on line 7—7 of Fig. III, and clearly shows a cam which is attached to a spindle, the spindle when rotated being of a character to rotate the cam in a manner to engage a part of the valve operating mechanism to render the same inoperative.

Considering the principles of design and construction embodied in the apparatus above described, in connection with the drawings, it will be noted that a majority of the working parts are arranged within a cabinet generally designated 1. The cabinet may be of any shape or form, however in the present instance it is composed of front and rear walls 2 and 3 respectively, side walls 4, and a bottom wall 9, all of which are supported on suitable legs 5. A tank 6 containing an exceptionally cold cooling medium is arranged in the cabinet and, as shown, is surrounded by side walls 7, a bottom wall 8, and tight fitting cover 10, all of which contain suitable insulating material. Thus the refrigerator for cooling the beverage is well insulated and located in the lower part of the cabinet. A part of the means for lowering and raising the movable coil 13 which contains a part of the beverage to be dispensed, including other means, are preferably installed in the cabinet above the refrigerator.

A coil of conduit 11, through which a refrigerant is circulated, is preferably arranged in the cooling medium near the surface thereof, in order that the movable coil 13 secured in a crate 14, may be lowered into the confines of the coil 11, so that the temperature of the beverage in the movable coil may be reduced considerably prior to its discharge from the apparatus. The ends 85 and 84 of the coil 11 preferably extend through a wall of the cabinet and communicate with an apparatus 12 of any suitable type, which is of a character to circulate a refrigerant through the coil conduit 11 in order to maintain

the cooling medium in the tank at a very low temperature, preferably below zero.

The beverage or other liquid to be dispensed is preferably circulated through the coil 13 by means of a supply tank 29, and a pressure tank 30 preferably located apart from the cabinet. The coil is connected to the supply tank 29 by a conduit 31 which extends through the cabinet and downwardly in order that the beverage will 10 first pass through the lowermost section 32 of the coil, and thus be thoroughly chilled prior to its discharge from the apparatus. A flexible connection 36 is provided intermediate the conduit 31 and the upstanding end 37 of the coil 13. 15 The other end of the coil 13 is extended upwardly as indicated at 33 and is connected to a dispensing valve or tap 35 by a flexible connection 34. The upstanding ends of the coil, including the cable 24 which supports the coil, are 20 movable through an opening 25 provided in the cover 10.

As stated above, one particular object of the invention is to provide means whereby the temperature of the beverage may be lowered considerably immediately preceding its discharge from the apparatus. This is accomplished by arranging a coil 13 within the refrigerator tank normally above the cooling medium, and providing means controlled by a foot treadle whereby 30 the coil may be lowered and immersed in the cooling medium, particularly within the confines of the coil of conduit 11, the coil 13 being automatically raised when the foot treadle is released.

35 The device for lowering the coil 13 with respect to the cooling medium involves the provision of a wheel or pulley 15 which is mounted upon a shaft 16 which is suitably supported in the cabinet. The wheel is provided with a groove in its periphery. The cable 24 is arranged in the groove, and one end thereof is connected to the rack 14 or to the coil 13 in any suitable manner, and its other end is secured to a weight 26, which serves to return the coil 40 normally above the cooling medium. The weight is movable within a well 27.

50 A bell crank 23 is mounted upon the shaft 16 and, as shown, the upper end of a connecting rod 17 is pivotally secured to the end of one arm of the crank at 18, and the lower end of the rod is pivotally connected at 20 to the forward end of a foot treadle 19, which extends part way under the cabinet. The treadle 19 is pivotally supported intermediate its ends upon an axle 21. 55 The axle is carried by brackets 22 which are secured to the bottom of the cabinet. The bell crank is not keyed to the shaft 16, therefore if the crank is not locked to the wheel by the latch 58, which will be described later, the crank will 60 be free to pivot with respect to the shaft. The other arm 57 of the bell crank has a latch 58 pivotally secured thereto as indicated at 40. The latch 58 is adapted to normally engage a pin 59 which extends transversely from a spoke of the wheel 15 by means of a spring 68, which has one end connected to the arm 57 of the crank and the other end to the latch. Thus when the treadle 19 is depressed by the foot, the bell crank, through the agency of the rod 17, and 65 the latch 58, will cause the wheel 15 to rotate in a clock-wise direction and lower the coil 13 into the cooling medium, and when the treadle is released the weight 26 will automatically return the coil 13 to its normal operative position 70 above the cooling medium. The rod 17 pref-

erably extends through a tube 28 provided in the rear wall of the refrigerator in order that the rod is free to move.

As above stated, a particular object of the invention is to provide means whereby the dispensing valve or tap may be operated at the same time that the coil 13 is lowered into the cooling medium. This is accomplished by the provision of a valve operating mechanism generally designated 38 which connects the bell 10 crank with the valve. This valve operating mechanism is comprised of a link 43 which has one end secured to a pivot 40, and its opposite end is pivotally connected at 39 to a rod 38. A tubular guide 37 is arranged in a horizontal position adjacent the upper part of the cabinet, and one end thereof is supported in a bracket 38, and the other end is secured to the front wall of the cabinet. One end of the rod 38 extends into the guide 37, and a rod 42 extends inwardly 20 from the other end. A link 45 is also arranged in the guide between the rod 38 and rod 42, and one end thereof is pivotally connected to the inner end of the rod 42 as indicated at 46. The rod 42 is operatively connected to the valve 25 through the agency of a link 43 and a bifurcated member 44. Thus when the treadle 19 is depressed, the valve 35, through the agency of the various connections, including the latch 58, will operate and open at the same time that the coil 30 13 is lowered.

35 A compression spring 47 is arranged on the guide 37 and provides means for automatically closing the valve when the coil 13 returns to its normal position above the cooling medium. A 40 washer 48 is also arranged on the guide and is held in relation thereto by means of a pin 49. The pin 49 is firmly anchored to the inner end of the rod 42. An elongated slot 50 is provided in one wall of the tubular guide and a similar slot 51 45 is provided in the opposite side of the guide. The ends of the pin 49 as clearly shown in Fig. III are adapted to extend through the slots 50 and 51. Thus the compression spring 47 is adapted to normally engage the washer 48 and force it 50 against the pin 49 in a manner to urge the rod 42 in a position to close the valve when the coil 13 is returned to its normal position above the cooling medium. It is to be understood that the spring 47 serves to close the valve whether the 55 valve operating mechanism is rendered inoperative or not.

The means employed whereby the valve operating mechanism may be rendered inoperative will now be considered. The top of the tubular 60 guide is preferably provided with an elongated aperture 89 in order that the link 45 may be lifted upwardly as clearly shown in Fig. V. A leaf spring 61 has one end connected to the tubular guide, and its opposite end is adapted to normally maintain the link 45 within the guide. The link 45 is provided with a right-angular member 66. The means for lifting the link 45 upwardly is hand controlled and, as clearly shown in Fig. III, a spindle 52 has one end supported 65 in a bracket 90, and its opposite end extends through the front wall of the cabinet and is provided with a knob 53. A cam element 54 is eccentrically connected to the inner end of the spindle 52. The cam is provided with a face 54' 70 as shown in Fig. VII. Thus by manipulating the spindle the cam element 54 may be turned so that the face 54' thereof will engage the right-angular member 66 and lift the link 45 upwardly and render the valve operating mechanism in- 75

operative. Thus by manipulating the spindle the valve operating mechanism may be rendered inoperative, and the valve may be operated manually without lowering the coil 13, or, if desired, the coil 13 may be lowered and held for any length of time in the cooling medium, and the valve in such case may also be manually operated as desired. Thus the temperature of the beverage may be cooled considerably prior to its discharge from the valve.

As above referred to, a further object of the invention is to provide means controlled by the foot whereby the dispensing valve may be manually operated without lowering the coil 13. In other words, a mechanism is provided for rendering inoperative the means for lowering the coil, and is thereby distinguishable from the hand controlled means above referred to for rendering the valve operating mechanism inoperative. The means for rendering the lowering means inoperative is controlled by the foot, and is of a character to lift the latch 58 out of engagement with the pin 59, and thereby disconnect the bell crank 23 from the wheel 15. As clearly shown in Figs. II and IV, the latch 58 is provided with a finger 82. A rod 55 is supported in the bracket 38, and one end thereof is bent as at 81 so as to engage the finger 82 when the rod is moved. The opposite end of the rod 55 is pivotally connected at 91 to one end of the arm of a bell crank 92, which in turn is pivotally mounted on a shaft 93. A lever 61 is shown pivoted at 62 to the treadle 19. A rod 64 is vertically arranged in a tube 65. The lower end of the rod 64 is adapted to rest upon the forward end of the lever 61, and the upper bent end 95 of the rod is adapted to engage the arm 94 of the bell crank 92 when the button 63 is pressed. A spring 96 as shown in Fig. III has one end thereof connected to the cabinet, 40 and its opposite end to the extreme end of the arm 94 of the bell crank 92 in order to maintain the bent end 81 of the rod 55 in a position so that it does not normally engage the finger 82 provided on the latch 58. The spring 96 also serves to force the rod 64 downwardly against the forward end of the lever 61 in order to normally maintain the button 63 in an elevated position as shown in Fig. II. Thus, when the button 63 is depressed, the rod 64 will turn the bell crank 50 92 and in turn operate the rod 55 in a manner so that the bent end 81 thereof will engage the finger 82 and lift the latch out of engagement with the pin 59. In such case, the dispensing valve 35 may be manually operated without turning the wheel and lowering the coil 13. It is to be understood in this connection that any of the various rods such as 17 and 39 may be lengthened or shortened as desired and that means may be provided for adjusting them.

As clearly shown in Figs. I and VI, a device 66 is preferably attached to the dispensing valve 35 and is comprised of a wiper blade 67 which is secured to a bifurcated member 68. A plate 69 is secured to the body of the valve by a clamp 71. By a bolt and spring arrangement 70, the bifurcated member 68 and the wiper blade 67 attached thereto are pivotally secured to the plate 69. The arrangement is such that the member 68 may pivot with respect to the plate 69 and may also laterally adjust itself thereto. This device is adapted to be arranged in a convenient location so that as each container is filled with the beverage the container may be lifted up and then swung in a horizontal position so that the wiper

blade 67 will engage the top of the container and remove the foam therefrom. Therefore the operator may remove the foam without the use of the stick which is usually used to perform this purpose.

A shelf 72 is preferably secured adjacent the front wall of the cabinet in a convenient position below the dispensing valve, and if desired a drain 73 may lead downwardly therefrom.

It is to be understood that the tank 6 if desired 10 may be provided with a drain 74, a thermometer 75 to determine the temperature of the cooling medium, and that a pressure gauge 76, and a valve 77 may be included in the apparatus. It is to be further understood that if desired a housing 15 78 with suitable compartments may be arranged in the bottom of the tank 6 below the coil 11 in order that trays such as 79 or other articles may be inserted into the housing and be cooled. The trays 79 may contain ice cubes, food or other 20 commodities. A door 80 is adapted to close the opening leading to the housing 78.

From the foregoing description, it will be evident that novel means are employed whereby the temperature of a beverage may be lowered considerably immediately preceding its discharge from the apparatus. Further, that means operable by a foot treadle are provided whereby the dispensing valve may be opened at the same time that the coil is lowered into the cooling medium. 30 It will also be evident that other means controlled by the foot are provided whereby the means for lowering the coil may be rendered inoperative in order that the dispensing valve may be manually operated without lowering the coil. 35 Furthermore, that means controlled by the hand are provided whereby the valve operating mechanism may be rendered inoperative in such a manner that the coil may be lowered as desired and the dispensing valve manually controlled, and 40 that means are provided for normally closing the dispensing valve after it is opened.

I claim:

1. A beverage dispenser comprising means containing a body of cooling medium, means containing a liquid to be cooled operatively related to said cooling medium, means operated by the foot for lowering the means containing the liquid into the cooling medium, and means including a weight for returning the means containing the liquid to 50 its normal position above the cooling medium.

2. A beverage dispenser comprising means containing a body of cooling medium, a coil arranged above said medium, means controlled by the foot for lowering the coil into the medium, a dispensing valve connected to said coil, and means controlled by the hand provided whereby the valve may be opened and closed regardless of the position of the coil with respect to the cooling medium.

3. A dispenser as set forth in claim 2, in which means are provided for automatically closing the valve.

4. A beverage dispenser comprising means containing a body of cooling medium, means containing a liquid to be cooled operatively related to said cooling medium, a discharge valve connected to the means containing the liquid to be cooled, and means for simultaneously lowering the means containing the liquid to be cooled into the cooling medium and operating the valve whereby the temperature of the liquid is lowered immediately preceding its discharge from the valve.

MARTIN SENESE.
